(57) **CLAIM**

The ornamental design for a fire pit, as shown and described.

DESCRIPTION

FIG. 1 is a bottom perspective view of a fire pit showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof;

FIG. 9 is an enlarged detail view taken from portion 9 of FIG. 2; and,

FIG. 10 is an exploded top perspective view thereof.

The broken lines in FIGS. 2 and 9 represent the boundary of the enlarged portion and form no part of the claimed design.
